(57) **CLAIM**

The ornamental design for a valve body for faucet, as shown and described.

DESCRIPTION

FIG. 1 is a perspective view of a first embodiment of a valve body for faucet showing my new design;

FIG. 2 is another perspective view thereof;

FIG. 3 is another perspective view thereof;

FIG. 4 is another perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof;

FIG. 11 is a cross-sectional view taken along the line 11-11 shown in FIG. 1;

FIG. 12 is a perspective view of a second embodiment of the valve body for faucet;

FIG. 13 is another perspective view thereof;

FIG. 14 is another perspective view thereof;

FIG. 15 is another perspective view thereof;

FIG. 16 is a front elevational view thereof;

FIG. 17 is a rear elevational view thereof;

FIG. 18 is a left side elevational view thereof;

FIG. 19 is a right side elevational view thereof;

FIG. 20 is a top plan view thereof;

FIG. 21 is a bottom plan view thereof; and,

FIG. 22 is a cross-sectional view taken along the line 22-22 shown in FIG. 12.
